(57) **CLAIM**

The ornamental design for a crawler pad for rubber crawlers, as shown and described.

DESCRIPTION

FIG. 1 is a front view of a crawler pad for rubber crawlers according to my new design;

FIG. 2 is a top view thereof;

FIG. 3 is a right side view thereof;

FIG. 4 is a left side view thereof;

FIG. 5 is a rear view thereof;

FIG. 6 is a fragmentary enlarged view taken along line 6-6 in FIG. 1; and,

FIG. 7 is a fragmentary enlarged view taken along line 7-7 in FIG. 1.

Features shown in broken lines are for illustrative purposes only, and form no part of the claimed invention.
